James Dykes, Attorney

UNITED STATES PATENT OFFICE.

JAMES DYKES, OF NEW ROCKFORD, NORTH DAKOTA.

PORTABLE CRANE.

1,213,603.

Specification of Letters Patent. Patented Jan. 23, 1917.

Application filed June 13, 1916. Serial No. 103,470.

To all whom it may concern:

Be it known that I, JAMES DYKES, a citizen of the United States, residing at New Rockford, in the county of Eddy and State 5 of North Dakota, have invented certain new and useful Improvements in Portable Cranes, of which the following is a specification.

This invention relates to portable derricks or cranes adapted more particularly for use in connection with railway cars, freight trucks and the like, and has for one of its objects to provide a simply constructed device which may be readily applied to and disconnected from the vehicle or contiguous to the vehicle, and whereby relatively heavy articles may be disposed upon or removed from the platform of the vehicle.

With these and other objects in view, the invention consists in certain novel features of construction, as hereinafter shown and described and then specifically pointed out in the claims; and in the drawings illustrative of the preferred embodiment of the invention—Figure 1 is an elevation of the improved device applied to a conventional railway car, the railway rail and the platform of the car being in section; Fig. 2 is a transverse section of the boom portion of the improved device, together with the carrier or traveler; Fig. 3 is a section on the line 3—3 of Fig. 1; Fig. 4 is an enlarged plan view of the mast and a portion of the boom illustrating the construction more fully; Fig. 5 is a side elevation of the parts shown in Fig. 4; Fig. 6 is a section on the line 6—6 of Fig. 5.

Corresponding and like parts are referred 40 to in the following description and indicated in all the views of the drawings by the same reference characters.

The improved device includes a support or standard represented as a whole at 10, 45 and tubular and adapted to support the mast portion 11 of the improved device. The member 10 is provided near the upper end with a plurality of bearing balls 12 against which the mast rotates and stepped 50 at its lower end at 13 in the bottom of the standard 10.

In Figs. 1 and 3 the standard 10 is provided with branching arms 15, each arm terminating in a hook 16 adapted to engage 55 over the head portion of a railway rail 17. Each arm 15 is likewise provided with a

brace 18, preferably integral therewith, and engaging the rail at the juncture of its web and flange, as shown in Fig. 1. By this means the member 10 is firmly supported 60 relative to the rail 17, and may be readily moved from place to place as required. The arms 15 are of sufficient length so that when applied to the rail the mast 11 will clear the side of the car platform, a portion of 65 which is represented conventionally at 19. The mast 11 may be of any required length and is preferably tubular as shown and is stiffened and strengthened by employing a plurality of L-bars 20 riveted together, as 70 disclosed in Fig. 4 and disposed within the member 11 longitudinally thereof. By this means the member 11 is materially strengthened and stiffened.

The mast portion 11 is designed to support a boom device, represented as a whole at 21, which is preferably formed of four L-bars riveted together in the form shown more particularly in Fig. 2. At the mast end the upper webs of the boom members are 75 provided with a strap device encircling the mast 11, as shown at 22, and extended and riveted or otherwise secured, as shown at 23, to the upper webs of the boom. Secured to the lower webs of the boom are other straps, 80 one of which is represented at 24, riveted or otherwise secured at 25 to the opposite face of the lower webs of the boom and partly embracing the mast 11, as shown at 26. The upper straps 22 operate to rotatively couple 85 the boom member to the mast while the lower strap members 24 serve as braces or steps to firmly support the boom in its position at right angles to the mast. An adjustable stop collar 26 is slidably disposed upon 90 the mast and held in place by a set screw or like device 27. The stop collar thus forms a bearing upon which the mast 21 swings and likewise operates to hold the boom in any 95 position upon the mast. By this means the boom may be adjusted toward and away from the platform 19 as required. A suitable traveler is provided and comprises a U-shaped hanger or yoke 28 carrying a grooved roller or trolley 29 which engages 100 the upper edges of the upper webs of the boom member, as shown in Figs. 1 and 2.

The yoke 28 carries a swiveled eye member 30 to which a hoisting mechanism may be attached, the latter not being shown as it 110 forms no part of the present invention. At its outer end the boom member is preferably

provided with a suitable stop 31 to prevent the traveler from running off from the free end of the boom.

It will thus be obvious that a simply constructed crane or derrick device is produced which may be quickly attached to one of the rails of a railway track and by means of which heavy articles may be quickly hoisted into position above the platform or removed 10 from the platform as may be required.

The improved device may be readily moved from place to place without detaching any of the parts.

The improved device is simple in construction, may be inexpensively manufactured and of any required size and of any required capacity.

The vertical webs of the L-members which form the body of the boom are wider than 20 the horizontal webs as shown, to increase the vertical strength.

Having thus described the invention, what is claimed as new is—

1. In a device of the class described, a

supporting standard, a mast mounted for 25 rotation in said standard, a boom device including vertically directed webs, a strap member connected to said boom device at its upper edge and encompassing said mast, stop members connected to said boom at its 30 lower edge and bearing against said mast, and a stop collar adjustable upon said mast and engaging said boom.

2. In a device of the class described, a supporting standard, a mast supported by 35 said standard, a boom formed of L-bars connected by their webs, a strap device connected to the upper webs of said boom and rotatively engaging said mast, brace members connected to the lower webs of said 40 boom below said strap device and bearing against said mast, and a stop collar adjustable upon said mast and engaged by said braces.

In testimony whereof I affix my signature.

JAMES DYKES. [L. S.]
